United States Patent Office.

JOHN LUKE HANLY, OF SAN FRANCISCO, CALIFORNIA.

Letters Patent No. 64,762, dated May 14, 1867.

IMPROVED ANCHOR-STOCK.

The Schedule referred to in these Letters Patent and making part of the same.

TO ALL WHOM IT MAY CONCERN:

Be it known that I, JOHN L. HANLY, of San Francisco, San Francisco county, State of California, have invented certain new and useful improvements in "Anchors;" and I do hereby declare the following description and accompanying drawings are sufficient to enable any person skilled in the art or science to which it most nearly appertains to make and use my said invention without further invention or experiment.

The nature of my invention is to provide an improved anchor-stock, in which I have succeeded in obviating the evil of breaking off at the point where the key passes through to secure it to the shank.

In order to accomplish this I make a key-way in one side of the opening in the shank through which the stock passes, and weld on the stock a flange at such a distance from the shoulder as to let the stock turn after the flange has passed entirely through. By turning the stock one-fourth or more of the circumference a key-way through the shoulder is brought into a line with the one in the shank, so that a key may be inserted to keep the shank and stock in their relative positions.

To more fully explain my invention reference is had to the accompanying drawings, forming part of this specification, of which—

Figure 1 is a perspective view.

Figure 2, a portion of the shank and stock with the flange and key-way.

Similar letters indicate like parts in each of the figures.

A represents the shank of the anchor, having the hole B passing transversely through it to admit the stock. A key-way, a, is cut in the opening B. The stock C is constructed with the shoulder b in the ordinary manner, but has a permanent flange, c, welded to it longitudinally. This flange takes the place of the pin or key usually put through the stock at that place, and which weakens it materially by taking away the metal from a point where strength is most necessary. The shoulder b has a key-way, d, cut through it at right angles with the position of the flange c on the stock, and parallel with the flange.

The flange c is placed at a distance from the shoulder b equal to the thickness of the shank, so that after passing entirely through the key-way a it allows the stock to be turned till the key-way d is in a line with a, when a key, D, is inserted, which holds the stock firmly in its place. The permanent flange c welded to the stock increases the strength at a point where it is most liable to break, for when the anchor falls with the end E down, as soon as the vessel draws on it that end will bind as the lower fluke begins to take hold, and when the stock is fastened by a key through it, it is very much weakened, and will be very liable to bend or break at that point. The other side will be strong enough on account of the shoulder b.

Having thus described my invention, what I claim, and desire to secure by Letters Patent, is—

An anchor-stock C, in combination with the permanent flange c and movable key D, substantially as and for the purpose herein set forth.

In witness whereof I have hereunto set my hand and seal.

JOHN L. HANLY. [L. S.]
